UNITED STATES PATENT OFFICE.

TIMOTHY HOLLAND, OF CHICAGO, ILLINOIS, ASSIGNOR TO MARY C. HOLLAND, OF SAME PLACE.

DESIGN FOR A RADIATOR-SECTION.

SPECIFICATION forming part of Design No. 29,294, dated August 30, 1898.

Application filed July 25, 1898. Serial No. 686,844. Term of patent 14 years.

To all whom it may concern:

Be it known that I, TIMOTHY HOLLAND, a citizen of the United States, residing at Chicago, in the State of Illinois, have invented and produced a new and original Design for a Radiator-Section, of which the following is a specification, reference being had to the accompanying drawings, forming part thereof.

Figure 1 is an end view of a radiator with sections showing my new design. Fig. 2 is a sectional view taken on the line 2 2 of Fig. 1.

As shown in the drawings, the leading or material feature of my design consists in a new, useful, and original shape or configuration of a separate tubular loop or section of which the radiator is composed. Said section comprises a central member A, two outer members A', and a series of intermediate members a. The central and outer members A A' are disposed in parallel relation at uniform distances apart and joined together at the top and bottom by inward extensions from

the outer members united upon the ends of the central member, as shown at a', and the intermediate members are disposed at uniform distances apart and in parallel relation with one another in the spaces between the central and outer members and joined to the last-named members, as shown at a², the lines of the intermediate members projecting similarly from corresponding points on opposite sides of the central member. The figures formed at opposite points by any two of the intermediate members with the two sides of the central member are the same.

Having described my invention, what I claim as new, and desire to secure by Letters Patent, is—

The design for a radiator-section substantially as herein shown and described.

TIMOTHY HOLLAND.
